WIRE STAPLE REMOVING TOOL

William G. Pankonin, Chicago, Ill.

Application November 12, 1949, Serial No. 6,010

Term of patent 14 years

(Cl. D74—1)

To all whom it may concern:

Be it known that I, William G. Pankonin, a citizen of the United States, residing at Chicago, in the county of Cook and State of Illinois, have invented a new, original, and ornamental Design for a Wire Staple Removing Tool, of which the following is a specification, reference being had to the accompanying drawing, forming a part thereof, and in which:

Fig. 1 is a side view; Fig. 2 a front view; Fig. 3 a top view; Fig. 4 a bottom view; and Fig. 5 a perspective view, of a wire staple removing tool, showing my new design.

I claim:

The ornamental design for a wire staple removing tool, as shown.

WILLIAM G. PANKONIN.
